BOAT STABILIZER

Joseph H. Jacobs, Minneapolis, Minn.

Application January 23, 1947, Serial No. 723,869

5 Claims. (CL. 114—126)

1

This invention relates to a boat stabilizer particularly adapted for use on small boats.

Most small boats are very unstable and they roll and tip easily. Every year a large number of deaths are caused by small boats overturning. In rough water and also when loading and unloading an unstable boat can be very dangerous.

It is an object of my invention to provide a portable stabilizer adapted to be readily attached to various types of small boats to substantially reduce rolling and tipping thereof.

More specifically it is an object of my invention to provide a submerged stabilizing member preferably in the form of a fin with readily attachable mounting means having a hinged relation between the stabilizer and said mounting means to enable the boat to navigate in very shallow water.

The above and other objects and advantages of the invention will more fully appear from the following description made in connection with the accompanying drawings, wherein like reference characters refer to the same parts throughout the views and in which:

Fig. 1 is a plan view of a boat showing the stabilizer attached thereto;

Fig. 2 is a side elevation of a boat with the stabilizer attached thereto;

Fig. 3 is a perspective view of the attaching element of the stabilizer; and

Fig. 4 is an enlarged view showing the hinged arm in detail; and

Fig. 5 is a central vertical sectional view of a portion of the attaching element.

A relatively small, submerged water engaging fin is provided and in the form of my invention illustrated takes the shape of a slightly elongated disc 8. This fin is, of course, made from any suitable metallic material which is heavier than water such as steel plate. A connecting arm 9 is disposed substantially vertically and has one end fixed to said fin or disc 8 and is hinged substantially at the center thereof as by a pin connection 10 shown in Fig. 4. The lower portion of 9b of arm 9 is disposed angularly of the upper portion of said arm so that the lower extremity 9b of said arm is disposed rearwardly of the transverse horizontal upper end portion 9a of the arm 9. The upper portion of said connecting arm 9 has a right angle bend therein forming a horizontal marginal end portion 9c. This horizontal portion 9c is journaled transversely of said boat in a gunwale attachment mounting 11 as shown in Fig. 5.

Gunwale attachment mounting 11 has an outer flange 11a and an inner flange 11b; a thumb

2

screw 12 is threadably mounted through inner flange 11b. A link 13 is pin connected at one end to the lower inward extremity of gunwale attachment mounting 11. The other end of said link 13 is pin connected to a supplemental bracing member 14 adapted to be mounted on a seat of the boat or any transverse member in said boat. Bracing member 14 in the form shown takes the shape of a U-shaped member having its two sides disposed horizontally in parallel spaced relationship. A thumb screw 15 is threadably mounted through the lower horizontal portion of said bracing member 14.

To install my stabilizer on a boat, the two downwardly disposed flanges 11a and 11b of gunwale attachment mounting 11 are slid down over the gunwale of the boat, the arm 9 extending downwardly on the outside of the boat and the disc 8 being submerged below the surface of the

water. The bracing member 14 is then slid over a seat or other transverse member of the boat and thumb screw 15 is tightened against the bottom surface of said seat or transverse member. The link 13 adapts said bracing member 14 to fit

seats which are disposed at varying distances below the gunwale of the boat. When the bracing member 14 has been secured to the transverse member in the boat, the gunwale attachment mounting 11 can be secured to the gunwale of the

boat by tightening thumb screw 12 against the inside surface of the gunwale, bringing the inner surface of outer flange 11a tightly against the outer surface of the gunwale. It will be seen that this mounting securely fastens the stabilizer to the boat.

In operation the submerged fin or disc 8 offers resistance to rolling and sudden tipping of the boat, tending to prevent it from overturning both during loading and unloading of the boat and also while it is navigating in rough water. When the boat comes into shallow water, the disc 8 engages the bottom and the arm 9 swings up both at hinge 10 and in the bushings in attachment mounting 11. The rearward disposition of the

lower portion of connecting arm 9 facilitates this pivotal action. This prevents injury to the disc or the boat when said disc strikes an obstruction in the water or comes in contact with the bottom of the lake or stream. The hinge 10 also makes the unit more portable and compact as does the pivotal connection in mounting 11.

It will be seen that an easily portable, collapsible, efficiently operating stabilizer has been provided for small boats and the like. My stabilizer is very easily installed on a great variety of small

boats and the water engaging disc or fin efficiently performs its function to stabilize the boat to resist rolling and overturning. A hunter or fisherman can easily carry one of my stabilizers with him and attach it to the side of a rented boat.

It will of course be understood that various changes may be made in the form, details, arrangement, and proportions of the various parts without departing from the scope of my invention.

What is claimed is:

1. A boat stabilizer comprising a fin at least partially submergible in water, an attachment mounting adapted to be secured to one side of a boat, and a depending connection between said fin and said attachment mounting, said connection having a pivotal joint therein, at an intermediate portion thereof, the lower segment being inclined rearwardly relative the vertical, said joint having its axis disposed in operation horizontally and transversely of said boat.

2. A boat stabilizer comprising a fin at least partially submergible in water, a mounting adapted to be attached to one side of a boat, and a depending connection between said fin and said mounting, said connection having a pivotal joint therein at an intermediate portion thereof, said joint having its axis disposed in operation horizontally and transversely of said boat, said mounting providing for swinging movement of said connection on a horizontal axis disposed transversely of said boat the lower segment of said depending connection sloping rearwardly to form an inclined lower segment adapted to swing upwardly upon striking an obstruction in the water.

3. A boat stabilizer having in combination a mounting bracket comprising a pair of depending spaced jaws adapted to receive an upstanding portion of the gunwale of a boat therebetween, a clamping element mounted on one of said depending jaws and adapted to be progressively shifted relative thereto to clamp the other jaw tightly against said gunwale portion, an elongated bearing fixed to said jaws and disposed transversely of said boat above the gunwale thereof; a fin at least partially submergible in water, a depending connecting arm fixed to said fin and having a transverse horizontally disposed element at

the top thereof journaled in said transverse bearing to pivotally mount said fin relative to said boat.

4. A portable boat stabilizer having a mounting bracket comprising a clamp adapted for rigid attachment to the gunwale of a boat, an elongated bearing disposed transversely of said boat and fixed to said gunwale attachment clamp, a diagonal brace connected at one end to said bearing and adapted to be rigidly clamped to a transverse member of said boat; a connecting arm having a transverse horizontally disposed element journaled in said bearing, and a submergible fin fixed at the lower end of said depending arm for stabilizing said boat.

5. A portable boat stabilizer having in combination a mounting bracket comprising a pair of spaced opposed depending jaws adapted to receive an upstanding portion of the gunwale of a boat therebetween, a clamping element threadably connected to one of said jaws for tightly clamping the other jaw against one side of said gunwale, a transversely disposed elongated bearing fixed to said jaws and disposed thereabove, a diagonal brace connected at one end to said bearing and having a clamp at the other end for rigidly attaching the same to a transverse member of the boat, a depending connecting arm having a transverse horizontally disposed element journaled in said bearing, and a submergible fin connected at the bottom of said arm for stabilizing said boat.
